W. F. VON HAMMERSTEIN

SAFETY RAZOR

Filed Sept. 12, 1924.

INVENTOR
W.F. von Hammerstein
BY *Werner & Co.*

ATTORNEYS

UNITED STATES PATENT OFFICE.

WILLIAM F. VON HAMMERSTEIN, OF LOS ANGELES, CALIFORNIA.

SAFETY RAZOR.

Application filed September 12, 1924. Serial No. 737,358.

To all whom it may concern:

Be it known that I, WILLIAM F. VON HAMMERSTEIN, a citizen of the United States, and a resident of Los Angeles, in the county of 5 Los Angeles and State of California, have invented a new and useful Improvement in Safety Razors, of which the following is a full, clear, and exact description.

My invention relates to improvements in 10 safety razors and more particularly that type of razor having three edges, and it consists in the combinations, constructions, and arrangements herein described and claimed.

An object of my invention is to provide a 15 safety razor of the character described having three cutting edges in which novel means is employed for permitting the user to keep track of which of the cutting edges have been used and therefore which edges are 20 fresh for use the next time the razor is used, and after the blade has been removed for cleaning.

A further object of my invention is to provide a safety razor in which particularly 25 novel mechanism is employed for holding the blade retaining member placed upon the razor so as to flex the guard sufficiently to turn the edge to the proper angle for shaving.

30 A further object of my invention is to provide a safety razor of the character described in which novel means is employed for preventing the blade from turning or shifting laterally when the blade retaining member 35 is in position.

A further object of my invention is to provide a safety razor of the character described in which the blade is so formed as to permit extreme flexibility at those portions adjacent 40 to the cutting edges, yet in which no possibility of splitting the blade is present, as in the case of ordinary blades in which radial splits are provided to permit the flexing of the blade.

45 A further object of my invention is to provide a safety razor of the character described in which the guard is held substantially rigid and in which the reenforcing members employed to establish rigidity do not in any way hinder the accumulation of lather upon the guard.

50 Other objects and advantages will appear in the following specifications and the novel features of the invention will be particularly 55 pointed out in the appended claims.

My invention is illustrated in the accom-

panying drawings forming a part of this application in which:

Figure 1 is a side elevation of an embodiment of my invention, 60

Figure 2 is a top plan view of the mechanism shown in Figure 1 with a portion thereof broken away.

Figure 3 is a bottom view of the mechanism shown in Figure 1. 65

Figure 4 is a sectional view along the line 4—4 of Figure 2,

Figure 5 is a sectional view along the line 5—5 of Figure 3, and

Figure 6 is a top plan view of one of the 70 blades.

In carrying out my invention I make use of a triangular shaped member 1 having portions of the side walls knurled as shown in Figure 2 so as to afford a non-slip grip 75 upon the handle. A triangular guard member 3 is mounted at the upper end of the handle 1 and is provided with reenforcing bars 4 extending from a point adjacent to the outer corners of the guard to the triangular shaped member 1 for a short distance beneath the guard. This structure leaves the entire space beneath the bars 4 free and thus the surface of the guard is left unobstructed between the opposite ends of the work engaging 80 edges so that lather may accumulate thereupon during the process of shaving and also so that the guard may be cleansed. 85

Additional reenforcing members are provided in rigid cross pieces 5 extending between each of the adjacent sides of the webs 4 to a point below the under surface of the guard 3 out of engagement with the side walls of the handle. An inscription is placed on each of the reenforcing members 90 5 denoting numerals from 1 to 3 inclusive.

The blade retaining member 6 (see Figure 4) is provided for retaining the flexible blade 7 in engagement with the guard 3 whereby the blade will be held in an operative position for use. 100

The member 6 is substantially triangular in contour and the upper surface is curved as shown at 8 so as to present a smooth area which will not irritate the flesh of the person using the razor as it is drawn over the face. The downwardly extending cylindrical lug 9 is centrally located on the under side of the retaining member 6 and is arranged to be received in a cylindrical socket 10 in the handle member 1 for the purpose 105 of preventing lateral movement of the re-

taining member relative to the handle when placed thereon.

Three radially extending bosses 11 are provided on the side wall of the cylindrical lug 9 adjacent to the surface of the retaining member 6 which are substantially in the shape of a triangle having their corners pointed toward the acute corners of the retaining members thus forming a cross section portion having the appearance of a disk superimposed upon the triangle (see section line of Figure 2). The radially extending portions 11 are to prevent rotation of the device relative to the handle 1 and recesses 15 are provided in the socket portion 10 corresponding to the triangular bosses on the lug 9.

The blade 7 has an aperture 12 therethrough which is similar in contour to the lug 9 adjacent to the under surface of the retaining member 6. Thus the blade is held against rotation when placed between the retaining member and the guard member 3.

This blade 7 is of an especially novel structure and is shown in Figure 6. Three cutting edges *a*, *b* and *c* are provided. Legends indicating numerals from 1 to 3 are inscribed upon the blade 7 in registration with the cutting edges *a*, *b*, and *c*, respectively. This is for the purpose of permitting the readjustment of the handle member on the guard 3 in precisely the same position as it occupied when the razor was last used so that the person using the razor may know which of the edges have been used and which remain fresh for future use. Obviously the blade 7 must be removed for cleansing and drying, and if no means of identification of position were provided it would be impossible to know which of the edges have been used.

The corners of the blade 7 are cut away, leaving an obtuse angle recess 13 at each corner so that the blade 7 may be readily fixed, i. e., bent downwardly toward the work engaging edges of the guard 3 in the manner shown in Figure 5.

Means for locking the retaining member 6 upon the guard member 3 with the blade 7 therebetween is provided in three spring metal substantially semi-circular locking members 14, pivotally mounted upon the retaining member 6 at 15. The guard member 3 has depending ribs 16 extending parallel with the pivotal mounting 15 of the locking members 14 by means of which curved portions 17 at the outermost ends of the locking members 14 may engage with the guard 3 so as to draw the spring locking members slightly, thus holding the retaining member 6 in close engagement with the blade 7. This causes the blade 7 to conform with the contour of the guard 3 and to lie in its proper operative position between the blade and the retaining member.

From the foregoing description of the various parts of the device the operation thereof may be readily understood. One of the important advantages of my improved safety razor is that exact accounting of the use and condition of the edges of the blade 7 may be had at all times. Let us assume that the person using the razor has shaved with the edges *a* and *b*, numbers 1 and 2, which are in registration with the reinforcing members 5 bearing legends 1 and 2. The blade may be removed and dried, and replaced with the legends 1 and 2 in registration with the legends 1 and 2 on the reinforcing members 5. On taking up the razor for shaving the user will note that the edge *c* of the blade 7, distinguished by the numeral 3 on the reinforcing member 5, is a fresh edge and may be used as such.

In fixing the blade 7 by locking the retaining member 6 upon the guard, there is no possibility of splitting the blade as in the ordinary type of triple-edge blade. This is made possible by the provision of an obtuse recess 13 in the corners at the angle. The blade 7 is substantially an equilateral triangle having a sixty degree angle between each of the adjacent edges. The angle between the side wall of the recess 13 is therefore 120 degrees, thus establishing the side walls of the recess perpendicular to the cutting edges *a*, *b*, and *c*.

In removing and replacing the blade 7, very little manual labor is required, since the release of any two of the locking members 14 will immediately permit removal of the retaining member 6 which may be replaced quickly, and the locking members placed into position over the ribs 16, as shown in Figure 5.

An accumulation of lather on the guard members 3 is not hindered in any way because of the reinforcing members 4 of the members 5, since these elements are carefully arranged upon the guard so as to free the upper space adjacent to the work engaging edge.

I claim:

1. A safety razor of the character described comprising a guard member, a handle for supporting said guard member, a triangular blade having three cutting edges, said blade being formed with recesses at each corner thereof, the side walls of the recesses being disposed at an obtuse angle from one another, and means associated with said guard member for clamping said blade to said guard member and for flexing said blade adjacent to each of the edges.

2. A safety razor of the character described comprising a guard member, a handle for supporting said guard member, a triangular blade having three cutting edges, and means for clamping said blade between said guard and said retaining member, said

means comprising spring locking members pivotally secured at one end to the retaining member and arranged to extend downwardly into engagement with the under surface 5 of said guard.

3. A safety razor of the character described comprising a triangular guard member, a handle for supporting said guard member, a socket of angular contour provided in the upper surface of said guard member, a triangular blade having a center opening therethrough arranged to register with the socket in said guard and conforming to the contour of said socket, a retaining member having a lug arranged to be projected through the opening in said guard member and to fit a socket in said guard member, whereby said retaining member and said blade are held against one another and said guard and means for locking said retaining member against movement away from said guard.

4. A safety razor of the character de-

scribed comprising a triangular guard member, a handle for supporting said guard member, reinforcing webs disposed between said handle and said guard member in registration with the corners of said triangular guard member, cross bars disposed between said web members below said guard member, a blade and a blade retaining means for securing said blade relative to said guard.

5. A safety razor of the character described comprising a guard member, a handle for supporting said guard member, a triangular blade having three cutting edges, said blade being formed with recesses in each corner thereof, the side walls of the recesses being disposed at right angles to the adjacent cutting edge, and means associated with said guard member for clamping said blade to said guard member and for flexing said blade adjacent to each of the edges.

WILLIAM F. von HAMMERSTEIN.
